United States Patent Office

Des. 195,773
Patented July 30, 1963

195,773

DENTAL UNIT

Robert V. Turner, 10808 Stanford Ave., Lynwood, Calif.

Filed June 11, 1962, Ser. No. 70,491

Term of patent 14 years

(Cl. D24—1)

FIG. 1

FIG. 2

FIG. 3

FIG.4

FIG.5

FIG. 6

FIG. 1 is a perspective view of a dental unit showing my new design, the bottom of the tray member not shown being flat and plain;

FIG. 2 is a side elevation thereof, with the movable control panel in an alternate position;

FIG. 3 is an elevation taken from the opposite side of FIG. 2;

FIG. 4 is an enlarged front elevation taken from the left of FIG. 2;

FIG. 5 is a rear elevation taken from the right of FIG. 2; and

FIG. 6 is a top plan view thereof.

I claim:

The ornamental design for dental unit, substantially as shown and described.
